Case A.

Hiram W. Hayden.

Design for a Lamp Burner.

4830

PATENTED APR 18 1871

Hiram W. Hayden

Augustus M. Berkely.

E. S. Hayden

United States Patent Office.

HIRAM W. HAYDEN, OF WATERBURY, CONNECTICUT, ASSIGNOR TO HOLMES,
BOOTH & HAYDENS, OF SAME PLACE.

Design No. 4,830, dated April 18, 1871.

DESIGN FOR A LAMP-BURNER.

The Schedule referred to in these Letters Patent and making part of the same.

To all whom it may concern:

Be it known that I, HIRAM W. HAYDEN, of Waterbury, in the county of New Haven and State of Connecticut, have invented or produced an ornamental Design for a Lamp-burner.

This design is shown in the annexed drawing by a side elevation.

The air-distributer *l* is made in the form of a flaring convex segment or zone, above which is the bead *m*, that projects beyond the air-distributer *l*, and *k* is the chimney-holder, made with open work of the shape shown.

The wick-tube *o* is slightly tapering, and the cone *r*,

between the air-distributer and wick-tube, terminates at its upper end with a cone at *s*.

The lamp-burner, made by associating the before-named parts of the shape shown, is neat and ornamental.

I claim as my invention—

The design of the shape and configuration of the parts of the lamp-burner combined together as represented.

Signed by me this 9th day of March, 1871.

Witnesses: H. W. HAYDEN.

AUGUSTUS M. BLAKESLEY,
E. S. HAYDEN.
